YARN WINDER

Abram P. Bell, Los Angeles, Calif.

Application October 14, 1938, Serial No. 235,047

2 Claims. (Cl. 242—111)

This invention relates to yarn winding and more particularly to a portable and collapsible yarn winder.

An object of the invention is to provide a simple, practical and inexpensive yarn winder as described.

Another object is to provide a portable and collapsible yarn winder.

Another object is to provide a yarn winder as described adapted to accommodate skeins of yarn of various sizes.

A further object is to provide a winder as described by which the yarn may be wound without drawing or excessively stretching the yarn.

Other objects and advantages will appear and be brought out more fully in the following specification, reference being had to the accompanying drawing wherein

Fig. 1 is a perspective view of an embodiment 20 of my invention in the open and operative position.

Fig. 2 is a view of the same in collapsed position and

Fig. 3 is a fragmentary view of the rotating 25 element of the same.

Referring more particularly to the drawing, I show a base member 5 preferably of wood or other suitable material, rectangular in shape and having rubber feet 6 and further provided with 30 a stop rod 7 extending outwardly from the side edges 8 of base member 5.

A pair of supports 9 are pivoted at 10 to sides 8 adjacent one end and are connected together by brace member 11 suitably secured thereto. A 35 hook 12 is secured to the end of base member 5 and is adapted to engage a pin 13 secured to brace member 11. Supports 9 are formed with grooves 14 in the upper ends thereof, which grooves are adapted to receive a trunnion rod 15 secured in 40 a groove in a block 16 which is connected by a pair of hinges 17 to a similar block 18. Block 18 is provided with a hook 19 by which it may be secured to a pin 20 on block 16. A pair of rods 21 are secured to each of blocks 16 and 18 and extend 45 outwardly therefrom and a block 22 is slid-

able on each pair of rods 21, having suitable holes therefor.

Each block 22 is provided with a spring cap member 23 suitably secured thereto having spring end portions 24 adapted to press against the 5 sides or rods 21.

The operation of the invention should be apparent from the foregoing description. A skein of yarn is placed between blocks 22 which are extended on rods 21 as far as may be necessary 10 to hold the skein securely but not too tightly. The yarn may then be wound into a ball causing rods 21 and blocks 16 and 18 to rotate around the trunnion axis. After the yarn is completely wound, the winder may be collapsed as shown in 15 Fig. 2.

Having described my invention, what I claim is:

1. A yarn holder comprising a base, a frame pivoted to the base and carrying two spaced 20 supports adapted to be swung in a vertical position and locked, a block formed of two members hinged together and clamping a shaft between the same forming trunnions removably mounted in the upper ends of the supports, two spaced 25 rods carried by each section of the block, and an adjustable member mounted on each pair of rods and spanning the space between the same.

2. A yarn holder comprising a base, a frame pivoted to the base and carrying two spaced supports 30 adapted to be swung in a vertical position and locked, the upper ends of the supports having grooves, a block formed of two members hinged together and clamping a shaft between the same forming trunnions resting in the 35 grooves in the upper ends of the supports, two spaced rods carried by each section of the block, and an adjustable member mounted on each pair of rods and spanning the space between the same, whereby the pivoted frame may be swung down 40 upon the base and the two sections of the block swung so as to bring the pair of rods above each other and placed flat upon the base.
